UNITED STATES PATENT OFFICE.

HUGH S. KERR, OF PHILADELPHIA, PENNSYLVANIA, ASSIGNOR TO LEEDOM, SHAW & STEWART, OF SAME PLACE.

DESIGN FOR CARPET.

Specification forming part of Design No. 7,728, dated September 1, 1874; application filed August 15, 1874.
[Term of Patent 3½ years.

To all whom it may concern:

Be it known that I, HUGH S. KERR, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

I claim as my invention—

The design for a carpet, as shown.

HUGH S. KERR.

Witnesses:

WILLIAM KERR,

JAMES H. KERR.
